UNITED STATES PATENT OFFICE.

CLARENCE A. BALDWIN, OF MIDDLETOWN, CONNECTICUT.

BLOCK-MOLDING APPARATUS.

1,232,177.

Specification of Letters Patent.

Patented July 3, 1917.

Application filed October 9, 1916. Serial No. 124,680.

To all whom it may concern:

Be it known that I, CLARENCE A. BALDWIN, a citizen of the United States, residing at Middletown, in the county of Middlesex and State of Connecticut, have invented certain new and useful Improvements in Block-Molding Apparatus, of which the following is a specification, reference being had to the accompanying drawings.

10 This invention relates to certain improvements in block molding apparatus and it is an object of the invention to provide a device of this general character having novel and improved means whereby the block, 15 after being molded, may be readily and conveniently removed from the mold.

It is also an object of the invention to provide a novel and improved apparatus including a core adapted to be moved into or 20 out of a mold and wherein the movement of the core into the mold is obtained automatically.

The invention also has for an object to provide an apparatus of this general character wherein the mold includes a plurality of movable walls together with automatic means coacting therewith for maintaining the same in assembled relation.

The invention consists in the details of 30 construction and in the combination and arrangement of the several parts of my improved molding apparatus whereby certain important advantages are attained and the device is rendered simpler, less expensive and otherwise more convenient and advantageous for use, all as will be hereinafter more fully set forth.

The novel features of the invention will hereinafter be definitely claimed.

40 In order that my invention may be the better understood, I will now proceed to describe the same with reference to the accompanying drawings, wherein—

Figure 1 is a view in end elevation of a 45 mold constructed in accordance with an embodiment of my invention, a second position of certain of the parts being indicated by dotted lines;

Fig. 2 is a fragmentary view partly in 50 elevation and partly in transverse vertical section of the device as herein embodied;

Fig. 3 is a longitudinal vertical sectional view taken through the device as herein dis-

closed and at substantially its transverse center;

Fig. 4 is a view in top plan of my improved apparatus as herein included, the supporting legs therefor being shown in fragment;

Fig. 5 is a view in bottom plan of the 60 pallet as herein employed; and

Fig. 6 is a view partly in top plan and partly in section of the block produced by my improved apparatus as herein disclosed.

As disclosed in the accompanying drawings, 1 denotes a base plate of predetermined dimensions and configuration and herein shown as rectangular in plan. The base plate 1 is maintained in predetermined spaced relation relative to a supporting surface through the medium of the legs 2 preferably arranged adjacent the corners of said base plate 1 and disposed downwardly on predetermined outward inclines.

At substantially its transverse center and 75 extending substantially the entire length thereof, the base plate 1 is provided with the opening or slot 3 through which is adapted to move the core C, said core C being preferably hollow with its lower wall provided at substantially its longitudinal center with an opening 4 through which extends a rod 5. The rod 5 has its upper end suitably secured to the top wall of the core C and extends a predetermined distance therebelow and is loosely directed through the bracket 6 depending from the base plate 1, and the lower end of said rod 5 has operatively engaged therewith, as at 7, the pitman 8 which is also operatively engaged, as 80 at 9, with the rock lever 10 pivotally engaged, as at 11, with the rod or bar 12 connecting a pair of longitudinally aligned legs 2.

The bracket 6 is substantially U-shape in 95 form and interposed between the base or said bracket 6 and the top wall of the core C is an expandable member 14 herein disclosed as a conventional coil spring encircling the rod 5 and which serves to normally 100 maintain the core C elevated.

15 and 16 denote, respectively, the side panels and end panels hingedly connected, as at 17, with the marginal portions of the base plate 1 and swinging in a vertical path, 105 the lower edges of said panels 15 and 16

setting upon the base plate 1 when in assembled or operative position with the end panels 16 overlying the adjacent vertical edges of the side panels 15 as is particularly illustrated in Figs. 2 and 4.

5 The outer faces of the panels 15 and 16 are provided with the vertically directed cam or wedge members 18 having their working faces inclined downwardly and inwardly. Coacting with each of said cams or wedge members 18 is a roller 19 or other anti-friction member rotatably mounted upon the frame 20 disposed around the panels 15 and 16 and having its longitudinal and transverse diameters in excess of the corresponding diameters of the molding chamber or compartment afforded when said panels 15 and 16 are in their assembled or operative relation.

10 Each end portion of the frame 20 at substantially its longitudinal center is provided with the depending rod 21 loosely directed through the guide bracket 22 depending from the adjacent end portion of the base plate 1. The lower portion of the rod 21 is operatively engaged, as at 23, with the pitman 24 which is also operatively engaged, as at 25, with the rock lever 26 pivotally engaged, as at 27, with the rod or bar 12.

15 Each of the brackets 22 includes a lateral extension 28 through which the rod 21 is disposed, and interposed between said extension 28 and the frame 20 is an expansible member 29 herein disclosed as a conventional coil spring encircling the rod 21 and which serves to constantly urge the frame 20 upwardly whereby it will be perceived that the coaction of said frame 20 or more particularly the rollers 19 carried thereby with the cam or wedge members 18, serves to maintain the panels 15 and 16 in assembled or operative relation.

20 The outer or free end portions of the levers 26 are connected by the treadle bar or beam 30 whereby it will be perceived that said levers 26 may be caused to be depressed in unison, and said bar or beam 30 also overlies the outer end of the lever 10; whereby said levers 10 and 26 will be depressed in unison.

25 The core C, when in its normal or elevated position, serves to divide the molding chamber or compartment into two sections, and insertible within each of said sections is a pallet 31. The adjacent extremities of the pallets 31 are connected by the plates 32 each of which at a point intermediate the pallets 31 is provided with an outwardly directed ear or extension 33 to afford means whereby said pallets 31 with the molded blocks thereof may be conveniently removed after the core C has been lowered or depressed and the frame 20 lowered in order to permit an opening movement of the panels 15 and 16. The end panels 16 are

provided in their lower marginal portions with the openings 34 through which the extensions 33 are disposed when said end panels are in their vertical or assembled position, and whereby it will be perceived that the extensions 33 offer no obstruction or hindrance to the operation of my improved molding apparatus.

30 As herein disclosed, it will be perceived that my improved molding apparatus will produce two blocks at an operation, it being understood that as the green material is placed upon the pallets 31 the same is suitably tamped or otherwise acted upon to assure the proper setting of the same. In practice I have found it of especial import to connect said blocks B with the ties T, the portion of said ties within the block being formed to afford the heads H whereby the strength of the blocks may be materially increased.

35 It will also be at once self-evident that the portion of the ties intermediate the blocks B, as is illustrated in Fig. 6, affords a convenient means whereby said blocks may be lifted or transported. In order to permit the proper positioning of the ties T within the blocks B during their formation, I provide the upper portion of the core C with the transversely directed open slots 35 as is believed to be clearly shown in Figs. 3 and 4.

40 In order to maintain the core C and the frame 20 lowered so that the operator may assist in the removal of the blocks formed within my improved apparatus, I have found it of advantage to provide one of the legs 2 with the latch 36 adapted to coact with one of the levers 26 as indicated by dotted lines in Fig. 1 of the drawings. By the use of the latch 36 it will be perceived that my improved molding apparatus may be readily operated by one man.

45 From the foregoing description, it is thought to be obvious that a molding apparatus constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

50 I claim:

55 1. A molding apparatus including a base plate, walls hingedly engaged therewith, each of said walls being provided with a cam member, a frame disposed around said walls and coacting with the cams thereof, auto- 130

matic means for constantly urging the frame in one direction for returning and holding the walls in assembled relation, and manually operated means for imparting movement to the frame in an opposite direction to permit a relative separation of the walls.

2. A molding apparatus including a base plate, walls hingedly engaged therewith, each of said walls being provided with a cam member, a frame disposed around said walls and coacting with the cams thereof, automatic means for constantly urging the frame in one direction for returning and holding the walls in assembled relation, and pedal operated means for imparting movement to the frame in an opposite direction to permit a relative separation of the walls.

3. A molding apparatus including a base plate, walls hingedly engaged therewith,

each of said walls being provided with a cam member, a frame disposed around said walls and coacting with the cams thereof, brackets depending from the base plate, rods secured to the frame and disposed through said brackets, expandible members interposed between the brackets and the frame for constantly urging the frame in a direction to maintain the hinged walls in closed relation, and pedal operated means operatively engaged with the rods for moving said frame in a direction to permit the hinged walls to be swung outwardly.

In testimony whereof I hereunto affix my signature in the presence of two witnesses. 35

CLARENCE A. BALDWIN.
